FACE POWDER BOX

Barbara B. Wheeler and Ralph V. Burdick, Jr.,
Loudonville, N. Y.

Application May 11, 1949, Serial No. 92,656

3 Claims. (Cl. 132—82)

1

Our invention relates to improvements in containers and packages and particularly to improvements in containers and packages of face powder.

At the present time, manufacturers of face powder in the loose, rather than caked form, pack the same in paper boxes practically all of which are cylindrical and consist merely of a container and a cover therefor. The container comprises a cylindrical side wall, a disk which conforms the bottom of the container, and a piece of cellophane which overlies and forms a tight but breakable cover or seal for the powder in the container. The cover proper merely slips over the side wall of the container like the cover of any round box.

In order to obtain access to the powder, the cellophane is torn away, and, thereafter, the powder is held in the box merely by the slip cover. Since the powder is impalpable, and the slip covers of paper boxes cannot be made to fit the container uniformly and tightly, it is quite impossible, after the cellophane seal is broken, to close the box so tightly that the powder is positively confined therein. Thus, it is impossible, for example, to carry such a loosely sealed box of powder in a suitcase without having the powder sift out between the cover and the container and cover all of the other articles in the case. Even when such a box is used on a lady's dressing table, there is no place to put the powder puff and, when a used powder puff is put in a dressing table drawer, other articles in the drawer eventually become covered with powder.

The general object of our invention is to provide a container for face powder with an easily removable cover but which can be so tightly sealed that the powder cannot leak therefrom. Another object is to provide a box for face powder in which a space is provided for carrying a powder puff. Another object is to provide a powder box which can be easily filled and sealed by the manufacturer. A further object is to provide a box which may be cheaply manufactured and which has an attractive appearance.

We attain these objects by means of the novel elements and the combinations and arrangements thereof described below and illustrated in the accompanying drawing, in which—

Fig. 1 is a plan view of our box with half of the cover removed;

Fig. 2 is a view half in elevation and half in section; and

Fig. 3 is a fragmentary vertical section through the box with the powder and puff therein.

2

Referring to the drawing, 1 is a cylindrical container for the powder which, like all of the other parts of the box, is formed of sheet metal having an outstanding circumferential bead 2 near the bottom thereof. It is not essential that the bead be closely adjacent the bottom of the box but we prefer to place it in that position because it gives the box a more attractive appearance. 3 is a first cover of the box which is formed in two parts and made to have a press fit with the container. When the first cover is seated on the container, the bottom 4 of the skirt thereof rests upon the bead 2.

In manufacturing the box, the top 5 of the first cover is provided with a large circular opening in which a centrally-disposed neck 6 is afterwards secured by rolling an outstanding circumferentially-extending bead 7 thereon to limit the extent in which the neck can enter said opening and by spinning or rolling the bottom 8 of the neck outwardly beneath the top 5, as shown at 9. The top of the neck 6 is provided with a circular depression 10 therein of a size adapted to receive the powder puff 16 shown in Fig. 3, and the bottom of the depression is provided with perforations 11 for the discharge therethrough of the powder 12 shown in Fig. 3. When the box is filled, the powder would not ordinarily extend above the upper rim of the container, but in Fig. 3 we have shown the box as filled up to the perforated depression.

In filling the box, the manufacturer merely fills the container to the desired level and then presses the first cover firmly thereon. The air which is entrapped between the first cover and the powder in the closing operation can freely escape through the perforations 11 in the bottom of the depression. The skirt of the first cover should fit tightly around the lateral wall of the container so that it cannot easily be removed, and thus forms a substantially permanent closure for the container.

In order finally to close the box, a second, easily removable cover 14 is provided having an arched top to form with the depression in the top of the first cover a space therebetween for the powder puff 16, and having a depending skirt 15 which slip-fits around the upstanding neck 6 of the first cover. The arched second cover not only imparts a pleasing appearance to the box but also cooperates with the powder puff when the second cover is seated to hold the puff in sealing relation with the perforations 11.

From the foregoing, it will be apparent that our box can be tightly sealed so that powder will

not sift therefrom, and that it is so designed that in packaging the powder and the puff together, no problems whatever are encountered.

What we claim is:

1. A powder box formed of four, separate, sheet metal elements including: a comparatively flat, cylindrical, powder-containing receptacle open at the top; a first cover element comprising a first portion having an inturned annular flange overlying the top edge of said receptacle, but otherwise open at the top thereof, and a depending skirt in tight engagement with the lateral wall of said receptacle; and a second, inverted, cup-like portion of smaller diameter than said cover portion having a re-entrant, perforated bottom, adapted to receive a powder puff, secured to the inner edge of said flange and extending upwardly therefrom; and a second cover element having a depending skirt in slip-fitted engagement with the lateral wall of said cup-like portion and an imperforate top adapted to cooperate with said puff when in the re-entrant bottom of said cup-like portion and hold it in firm engagement with said bottom.

2. A powder box comprising a comparatively flat, cylindrical, powder containing element, a first cover therefor having a centrally-disposed cylindrical neck portion of a diameter which is substantially smaller than said cover portion and projecting upwardly therefrom, the walls of which are inwardly directed marginally a substantial distance from the top peripheral edge of said cover and connecting the bottom of said neck by a substantially flat, horizontal, ring-shaped section providing an exterior landed hand-rest portion, a depression in the top of said neck, disposed above said ring-shaped section, of a size adapted to receive a powder puff and having perforations in the bottom of said depression; and a second, readily removable cover of a diameter which is smaller than said first cover cooperating with said upstanding cylindrical neck and adapted to cooperate with said powder puff when in said depression to hold said puff in firm contact with the bottom of said depression to form 45 a closure for said perforations.

3. A face powder box formed of sheet metal and comprising a comparatively flat, cylindrical container element having an outstanding circumferential bead adjacent the bottom thereof, a 5 first cover element having a force fit with said container element and laterally enclosing said container element between the top thereof and said bead; said cover element having a centrally disposed, upstanding, cylindrical neck portion of 10 a length and of a diameter which is substantially smaller than said cover portion, the walls of which are inwardly directed marginally a substantial distance from the peripheral top edge of said cover, connecting the bottom of said neck 15 by a substantially flat, ring-shaped section and providing an exterior landed hand-rest portion, a depression in the top of said neck, disposed above said ring-shaped section, to receive a powder puff and having perforations in the bottom 20 of said depression adapted to underlie and be closed by said puff when in said depression; and a second cover element of a diameter which is also smaller than said first cover element, and having a slip fit with said upstanding cylindrical neck portion, and having an arched top adapted 25 to cooperate with said puff when in said depression and to hold said puff in firm perforation-closing relation with the bottom of said depression.
